US00D977926S

(12) **United States Design Patent** (10) Patent No.: **US D977,926 S**
(45) Date of Patent: **** Feb. 14, 2023**

(54) **SAW BLADE**(71) Applicant: **MILWAUKEE ELECTRIC TOOL CORPORATION**, Brookfield, WI (US)(72) Inventors: **Robert W. Butzen**, Colgate, WI (US); **Austin J. Kazda**, Wauwatosa, WI (US); **Andrew J. Schulz**, Slinger, WI (US)(73) Assignee: **MILWAUKEE ELECTRIC TOOL CORPORATION**, Brookfield, WI (US)(***) Term: **15 Years**(21) Appl. No.: **29/757,541**(22) Filed: **Nov. 6, 2020****Related U.S. Application Data**

(63) Continuation of application No. 16/835,478, filed on Mar. 31, 2020, now Pat. No. 11,141,805, which is a continuation of application No. 16/158,474, filed on Oct. 12, 2018, now Pat. No. 10,639,732, which is a continuation of application No. 14/295,449, filed on Jun. 4, 2014, now Pat. No. 10,112,244, which is a continuation of application No. 13/570,401, filed on Aug. 9, 2012, now Pat. No. 8,776,659, which is a continuation of application No. 13/092,498, filed on Apr. 22, 2011, now Pat. No. 8,689,667.

Milwaukee Electric Tool 49-22-1129 Sawzall Reciprocating Saw Blade Set, Part No. 49-22-1129, ASIN: B000BYAZLE, online on Amazon.com, Date First Available: Oct. 2, 2003.*

(Continued)

Primary Examiner — Richard E Chilcot(74) *Attorney, Agent, or Firm* — Michael Best & Friedrich LLP(57) **CLAIM**

We claim the ornamental design for a saw blade, as shown and described.

DESCRIPTION

The FIGURE is a side view of a saw blade. Portions of the saw blade shown in broken lines form no part of the claimed design.
